UNITED STATES PATENT OFFICE.

FRANÇOIS CARVES, OF ST. ETIENNE, FRANCE.

COKE-OVEN.

SPECIFICATION forming part of Letters Patent No. 287,905, dated November 6, 1883.

Application filed May 9, 1883. (No model.) Patented in England June 28, 1879, No. 2,616.

To all whom it may concern:

Be it known that I, FRANÇOIS CARVES, a citizen of France, residing at St. Etienne, Department de la Loire, France, have invented 5 new and useful Improvements in Coke-Ovens, (for which Letters Patent for Great Britain have been obtained, No. 2,616, dated June 28, 1879,) of which the following is a specification.

10 My invention relates to a construction and arrangement of coke-ovens and apparatus connected therewith, whereby the coking of coal is more completely effected than in coke-ovens of ordinary construction, with an economy of fuel, and the tar, ammoniacal, and other products from the distillation of the coal are collected in a condition which renders them more readily available for use. Each oven, according to this invention, is in the well-known 15 form of a long narrow chamber of brick-work, and a number of these are built side by side, with partition-walls between them sufficiently thick to contain flues. Flues are also formed under the floor of each oven, and at one end 20 of these is a fire-place, consisting of a fire-grate and ash-pit with suitable doors, the fire-door having fitted above it a nozzle, through which air and gas produced from the coking are admitted to form a flame over the fuel 25 burning on the grate. The products of combustion pass from the fire-place along a flue under the oven-floor to the end farthest from the fire. They may return along another flue under the floor to the fire end. They then as- 30 cend by a flue in the partition-wall to the up- 35 permost of several flues formed therein, and descend in a zigzag direction along these flues, finally passing into a horizontal channel leading to a chimney. Thus the coke-oven is 40 heated not only at the bottom in the usual manner, but also at the sides, the heat being distributed in a very uniform manner by causing the combustion-gases to travel downward in the zigzag flue, as described, and the coal 45 with which the oven is charged becomes rapidly and completely coked, while the principal part of the heat of the fuel and gas consumed at the fire-place is utilized. The ovens are fed with coal by openings in the roof, over 50 which the coal-trucks are run on rails, and

the coal is evenly distributed by rakes introduced at end openings provided with doors faced with refractory material, that can be closed and tightly luted while the oven is in operation. The feed-holes in the roof are also 55 provided with covers that are closed tightly. Through the middle of the roof rises a gas-pipe provided with a hydraulic valve, which closes the passage by a lip projecting down from it into an annular cavity surrounding its 60 sealing, in which it is immersed in a portion of tar and ammoniacal liquor lodged there during previous distillation. The products of the coal distillation which come off in gaseous form rise by the gas-pipe, and are led 65 through a range of pipes kept cool by external wetting, so that the tar and ammoniacal liquor become condensed and separated from the combustible gas. These cooling-pipes are conveniently arranged in pyramidal form, sur- 70 mounted by a water-pipe having numerous holes, so that a shower of water descending on the uppermost of the cooling-pipes and on the outermost is scattered over all their surfaces. The gas, when separated from the con- 75 densed materials, is passed through scrubbers or vessels containing coke moistened by the ammoniacal liquor, which, being repeatedly used, becomes stronger and stronger until it reaches saturation, when it is run off into 80 reservoirs to be treated in the ordinary way for the preparation of ammonia and its com- pounds. The gas, being sufficiently purified, is led by pipes to the nozzles at the fire-places 85 of the ovens, where it is burned. It is preferred to employ exhausters to draw off the gaseous products of distillation, and when these are employed the hydraulic valves of the ovens that are open for charging and discharging have to be carefully closed, in order to prevent 90 admixture of air with the combustible gases.

In the drawings, Figure 1 is a transverse section, partly in elevation, of a range of several coke-ovens according to this invention. Fig. 2 is a longitudinal section through one of the 95 partition-walls. Fig. 3 is a plan on the line X-X of Fig. 1, and Fig. 4 is a longitudinal section through one of the ovens. Fig. 5 is a transverse section through the cooling-pipes, showing the pyramidal arrangement thereof. 100

M is the fire-place, from which the products of combustion pass by flues *a b c*, under the floor of the oven F, to ascending-flues *d e*, formed in the side and partition walls, whence 5 they pass by zigzag flues *e f g h i j* in these walls to the descending-flue *j k*, whence they are conducted by the horizontal flue L to the chimney-shaft. Feeding-holes B (which can be tightly closed by covers) are provided 10 through the crown of the oven, and, for convenience of feeding, the fuel-supply may be brought over these holes in trucks running on rails, as shown in Fig. 4. Through the crown of each oven rises the gas-pipe P, branching 15 into a valve-box, X, in which there is a valve, V, that can be lowered over a lip, T, projecting upward, so that there is a liquid-seal for the valve. When the valve V is raised, as shown in Fig. 4, the gaseous products of the 20 coking pass by the pipes R and U to suitable exhausters, being cooled on their way by passing through coils of pipes exposed to currents of air or water. These coils are with advantage arranged in pyramidal form, as shown at 25 Fig. 5, and wetted by water issuing by numerous perforations from a pipe, Q, placed above the highest length of the pipe-coil. The cooling effected by the passage of the gaseous matters to and fro through this coil effects con- 30 densation of the tar and ammoniacal liquor, which are allowed to flow into vessels, where they are separated by settlement. The uncondensed gases pass from the exhauster through scrubbers, consisting of columns of coke, which 35 are moistened with some of the ammoniacal liquor separated from the tar, the liquid being thus rendered stronger by further condensation from the gas during its passage through the scrubbers. From the scrubbers the gas is led 40 by a pipe, S', and branches N, provided with stop-cocks *n*, to nozzles Y, opening into the fire-places above the fuel on the fire-grate. The flame, passing along the flues above described,

heats both the floors and the sides of the ovens, so that the coking proceeds with uniformity 45 and rapidity.

I am aware that patents heretofore issued for coke-ovens describe the leading off and treating of the distilled gases, and also that closed coke-ovens have been heated by external firing. 50

Having thus described the nature of my invention and the best means I know of carrying the same into practical effect, I claim—

1. In a closed coke-oven heated by external firing, the combination of the coking-chambers, 55 the partition-walls, the horizontal zigzag flues in the partition-walls, communicating at their upper ends with the flues beneath the bed of the oven leading from the firing-place, and at their lower ends with the chimney, so that the 60 hot combustion-gases shall pass to the top of the zigzag flue and travel downward therein before escaping to the chimney, substantially as described.

2. The combination of the closed coke-ovens 65 heated by external firing, the heating-flues beneath the bed of the ovens, the horizontal zigzag flues in the side walls, and the described means for leading off the combustible gases distilled from the coal, separating therefrom the 70 condensable by-products and using them for combustion, as and for the purposes described.

3. The combination of the fire-place M, flues *a b c*, under the floor of the oven F, ascending-flues *d e*, formed in the side and partition walls, 75 zigzag flues *e f g h i j*, descending-flues *J K*, and horizontal flue L, leading to the chimney-shaft.

In testimony whereof I have signed my name to this specification, in the presence of two sub- 80 scribing witnesses, this 16th day of April, A. D. 1883.

FRANÇOIS CARVES.
